W. S. WELLS

BEAM SUPPORTING MEANS

Filed Nov. 22, 1923

Patented Dec. 2, 1924.

UNITED STATES PATENT OFFICE.

WILLIAM S. WELLS, OF SOUTH BETHLEHEM, PENNSYLVANIA, ASSIGNOR TO PENJAMIN EASTWOOD COMPANY, OF PATERSON, NEW JERSEY, A CORPORATION OF NEW JERSEY.

BEAM-SUPPORTING MEANS.

Application filed November 22, 1923. Serial No. 676,225.

To all whom it may concern:

Be it known that I, WILLIAM S. WELLS, a citizen of the United States, residing at South Bethlehem, in the county of Lehigh and State of Pennsylvania, have invented 5 certain new and useful Improvements in Beam-Supporting Means, of which the following is a specification.

This invention relates to means for supporting rotary beams, as the warp beam in a loom, and it has for its object to provide a beam-supporting means which can be quickly and easily adjusted both up and down to change the elevation of the beam or 10 laterally (i. e., longitudinally of the axis of the beam) so as to accommodate beams varying in width, and which shall afford a strong and rigid support for the beam.

In the drawing, 20 Fig. 1 is a side elevation of the rear part of a loom having the improved supporting means attached thereto;

Fig. 2 is a plan view of the end of the beam and said supporting means and 25

Figs. 3 and 4 are sectional views on lines 3—3 and 4—4, respectively, Fig. 1.

In the following description, only one end of the beam being shown in the drawing, only one of the supporting means is 30 referred to, it being understood that said supporting means will usually be duplicated in practice, there being one for each end of the beam.

a is the loom frame, *b* is a beam and *c* 35 its gudgeon, and *d* is the usual rope round the flanged head *b'* of the beam and having its rear and forward ends carrying weights *d'* and *d''*, the former of which maintains the tension on the warp *A* and the latter 40 of which by contacting with the floor allows in the known way for slippage to take place between the rope and the beam; whether this thus-weighted rope or any other means for maintaining tension on the warp is employed is of course immaterial.

Each side of the loom frame is provided 45 with a pivot, here in the form of a long stud *e*, projecting laterally and horizontally, being rigidly held in place by extending through a hole in said side of the frame 50 and having nuts *f* to clamp the same. On this pivot is movable up and down pivotally and also longitudinally thereof a rearwardly extending arm *g* having its top and bottom 55 edge portions straight and preferably

flanged at both sides (so as to present substantially an I-section, Figs. 3 and 4), as at *g' g''*.

On the upper flanged edge *g'* of the arm is arranged a block *h* which is fitted thereto, 60 having a T-shaped way *h'* formed therein to receive said edge. This block has an up-standing U-shaped or open bearing *i* to receive the beam gudgeon and it is also equipped with a set-screw *j* which may bind 65 against the arm; the block is adjustable lengthwise of the arm and when so adjusted may be held by the set-screw. The free end of the arm is supported as follows:

A bracket *k* is bolted to the side of the 70 loom frame below stud *e* and is equipped with a vertical pin *l* forming a pivot. On this pivot is pivotally movable another arm *m* which preferably has its free or rear end bent upward and formed with a vertical bearing *m'*. On this bearing rests a nut *n* which it is convenient to form with an extended circular portion or wheel *n'* affording a hand-grip. A vertical screw *o* is threaded into the nut and extends freely 75 through (i. e., without threaded engagement with) the bearing; *p* is a lock-nut on the screw below the bearing. At its upper end the screw has pivoted thereto, as on the horizontal bolt *q*, a slide *r* which is fitted 80 to the lower flanged edge *g''* of the arm *g*, having an inverted T-shaped way *r'* formed 85 therein to receive said edge.

The connection between the two arms *g* and *m* which is afforded by screw *o* and 90 slide *r* is one capable of rotation on a vertical axis relatively to *m* and of sliding relatively to and lengthwise of *g*. Consequently the lateral movements of the two arms (the one rectilineal and the other 95 pivotal) in adjusting the supporting means according to the length of the beam to be supported occur in unison, said connection turning in arm *m* and shifting lengthwise of arm *g*. When the nut *p* is screwed up 100 tight against bearing *m'* of arm *m*, so that the bearing is clamped between *p* and *n*, the entire structure is held rigid.

By turning the nut *n*, nut *p* being released, the screw *o* can be fed up and down 105 thus to raise or lower arm *g* and consequently place the beam at any desired elevation.

A bend is shown at *g** in arm *g* (Fig. 2). This, taken with the fact that the stud 110

may be arranged to project inwardly or outwardly from the side of the loom frame and the two arms *g* may be changed about, makes it possible to use the improved supporting means to support beams varying from a length which would bring the ends thereof between the sides of the frame to a length which would bring their ends outward of said sides.

10 The connection *o-r* also makes it possible for the weaver to quickly lower the supporting means so as to bring both weights *d' d''* against the floor and so relax the tension on the warp, as when the 15 loom is left standing over night, and also quickly restore said means to its previous elevation when the weaving is resumed.

The improved supporting means also adapts the loom to be quickly converted for 20 operation either with or without the usual whip-roll *s* being used to support the warp.

So far as lateral adjustment is concerned my invention comprehends broadly a beam supporting means including two arms, as 25 *g* and *m*, one of which is substantially horizontally shiftable, and the other of which is pivotally movable on a substantially vertical axis, on a fixed structure, as *a-e*, and a pivotal coupling (of any kind) having its 30 axis substantially vertical and connecting portions of the arms remote from said structure and shiftable along one arm.

Having thus fully described my invention what I claim is:

35 1. In combination, a fixed structure and a beam-supporting means including two arms one of which is substantially horizontally shiftable, and the other of which is pivotally movable on a substantially vertical axis, on said structure, and a pivotal coupling having its axis substantially vertical and connecting portions of said arms remote from said structure and shiftable lengthwise of one arm.

40 2. In combination, a fixed structure and a beam-supporting means including two arms one of which is substantially horizontally shiftable, and the other of which is pivotally movable on a substantially vertical axis, on said structure, and a connection shiftable along and held against turning relatively to one arm but turnable in the other arm on a substantially vertical axis.

45 3. In combination, a fixed structure and a beam-supporting means including two arms one of which is substantially horizontally shiftable, and the other of which is pivotally movable on a substantially vertical axis, on said structure, one of said arms being also pivotally shiftable relatively to the other up and down, and means, pivotally connecting the two arms in their various positions, and having its axis substantially vertical, for adjusting the up-and-down shiftable arm to different elevations.

50 4. In combination, a fixed structure and a beam-supporting means including two arms one of which is substantially horizontally shiftable, and the other of which is pivotally movable on a substantially vertical axis, on said structure, and a connection shiftable along and held against turning relatively to one arm but turnable in the other arm on a substantially vertical axis.

55 5. In combination, a fixed structure and a beam-supporting means including two arms one of which is substantially horizontally shiftable, and the other of which is pivotally movable on a substantially vertical axis, on said structure, and a connection shiftable along and held against turning relatively to one arm but turnable in the other arm on a substantially vertical axis.

60 6. In combination, a fixed structure and a beam-supporting means including two arms one of which is substantially horizontally shiftable, and the other of which is pivotally movable on a substantially vertical axis, on said structure, and a connection shiftable along and held against turning relatively to one arm but turnable in the other arm on a substantially vertical axis.

tively to the other up and down, and a connection connecting portions of said arms remote from said structure and comprising pivotally connected parts one of which is shiftable along one arm and the other turnable on a substantially vertical axis in the other arm.

70 4. In combination, a fixed structure and a beam-supporting means including two arms one of which is substantially horizontally shiftable, and the other of which is pivotally movable on a substantially vertical axis, on said structure, and means, pivotally connecting the two arms in their various positions and having its pivot substantially vertical, for securing them in rigid relation to each other.

75 5. In combination, a fixed structure and a beam-supporting means including two arms one of which is substantially horizontally shiftable, and the other of which is pivotally movable on a substantially vertical axis, on said structure, means, shiftable along and held against turning relatively to one arm but turnable in the other arm on a substantially vertical axis, for connecting the two arms in their various positions, and means to secure the first-named means against movement with respect to one of the arms.

80 6. In combination, a fixed structure and a beam-supporting means including two arms one of which is substantially horizontally shiftable, and the other of which is pivotally movable on a substantially vertical axis, on said structure, one of said arms being also pivotally shiftable relatively to the other up and down, and means, pivotally connecting the two arms in their various positions, and having its axis substantially vertical, for adjusting the up-and-down shiftable arm to different elevations.

85 7. In combination, a fixed structure and a beam-supporting means including two arms one of which is substantially horizontally shiftable, and the other of which is pivotally movable on a substantially vertical axis, on said structure, one of said arms being also pivotally shiftable relatively to the other up and down, and means pivotally connecting the two arms in their various positions and including a vertical screw arranged in one arm and a nut on the screw bearing against the latter arm, for adjusting the up-and-down shiftable arm to different elevations.

90 In testimony whereof I affix my signature.

WILLIAM S. WELLS.
